US00D839448S

(12) **United States Design Patent** (10) **Patent No.:** **US D839,448 S**
(45) **Date of Patent:** **** Jan. 29, 2019**

(54) **CUVETTE**

(71) Applicant: **BD Kiestra B.V.**, Drachten (NL)

(72) Inventors: **Brian Reuben Langhoff**, Julian, NC (US); **William Alan Fox**, Lake Wylie, SC (US); **Kerry Lynn Smith**, York, PA (US); **Stefan Campbell Dehaseth**, Baltimore, MD (US)

(73) Assignee: **BD Kiestra B.V. (NL)**

(**) Term: **15 Years**

(21) Appl. No.: **29/627,905**

(22) Filed: **Nov. 30, 2017**

Related U.S. Application Data

(62) Division of application No. 29/540,916, filed on Sep. 29, 2015, now Pat. No. Des. 808,036.
